(57) **CLAIM**

The ornamental design for a bodywork of a roller cabinet, as shown and described.

DESCRIPTION

FIG. 1 is a perspective view of a bodywork of a roller cabinet showing my new design;

FIG. 2 is a front view thereof;

FIG. 3 is a rear view thereof;

FIG. 4 is a left side view thereof;

FIG. 5 is right side view thereof;

FIG. 6 is a top view thereof; and,

FIG. 7 is a bottom view thereof.

The broken lines shown in FIGS. 1-7 are for the purpose of illustrating the environment of the design only and form no part of the claimed design.

The broken lines that define the bounds of the claimed design form no part thereof.
